F. H. WAGNER

LIQUID AND GAS CONTACT APPARATUS

Filed June 17. 1925

Fig. 3. Inventor:
Frederick H. Wagner,

by Dodge and Dow,
Attorneys.

UNITED STATES PATENT OFFICE.

FREDERICK H. WAGNER, OF BALTIMORE, MARYLAND, ASSIGNOR TO THE BARTLETT HAYWARD COMPANY, OF BALTIMORE, MARYLAND, A CORPORATION OF MARYLAND.

LIQUID AND GAS CONTACT APPARATUS.

Application filed June 17, 1925. Serial No. 37,796.

This invention pertains to an improved liquid and gas contact apparatus or to that type of apparatus commonly known in the art as a scrubber.

5 The main object of the invention is to provide a scrubber wherein intimate contact will be effected between the gas and the liquid. A further object of the invention is to provide means for ensuring the passage

10 of the gas through the liquid, not only through that portion of the liquid which is mechanically sprayed but also through the liquid as it re-flows from the spraying means to the pan or receptacle from which

15 it is drawn by the mechanical sprayer.

The invention is illustrated in connection with a typical Feld scrubber (Patent No. 983,037) and there is provided in the instant case means for securing a bubbling action of

20 the gas through the re-flowing liquid by the use of a bubble plate and caps. Means is also provided for maintaining a proper level of the liquid upon the bubble plate and likewise means to prevent a surge of the sprayed liquid back over said plate, which would interfere with the proper bubbling action.

In the drawings, Fig. 1 shows the apparatus in vertical sectional elevation;

30 Fig. 2 a top plan view of a portion of one of the bubble plates;

Fig. 3 an enlarged detail vertical sectional view of a portion of one of the bubble plates, the underlying pan and the spraying means;

35 Fig. 4 a sectional plan showing a modified form of the bubble cap.

As above noted, the invention is shown in connection with the so-called Feld scrubber, though it is to be understood that, in so far as the generic invention is shown, any means may be employed for pumping and spraying the liquid in the various sections of the scrubber.

45 In the drawings, 1 denotes the shell or casing provided at its lower portion with a gas inlet port 2, and at its upper portion with a gas outlet 3, which latter opens into an eliminator chamber 4 provided with any preferred type of eliminator shown in the instant case as a series of plates 5. Extending vertically through the casing is a shaft 6 driven through any suitable means (not shown), and provided at its lower end with a liquid seal designated by 7 to prevent pas-

sage of gas and liquid out and around the lower end of the shaft. A packing box may be employed.

A suitable draw-off 8 for the liquid extends into the bottom of the casing and liquid is supplied to the various impeller elements through pipes 9. It is to be understood, however, that any means for supplying the liquid may be employed.

In the drawing, Fig. 1, there is shown two pumping and spraying elements, though it will be understood that a greater or less number may be employed according to the capacity for which the apparatus is designed. The structure shown divides the apparatus into two chambers, each having a pumping and spraying element therein, and consequently a description of one will suffice for both.

Secured to the shaft 6 is a series of inverted truncated cones designated generally by 10, the outermost member of which adjacent its upper end is provided with a series of perforations 11. The cones at their lower ends dip into the liquid contained in a pan 12 which is provided with a series of radially disposed surge breaking plates 13. Upon rotation of the cone-shaped members 10, liquid is drawn upwardly thereby and thrown outwardly through the perforations 11 against the walls of the casing 1. This produces a fine dispersion of the liquid, and the gas passing upwardly therethrough comes into intimate contact therewith and is thoroughly washed by such gas.

The pans 12, as will be seen, stand in spaced relation to the wall of the casing and the gas passes freely therearound, and would pass directly upward through the apparatus and through the spray above mentioned were not some obstruction put in its way. To prevent this free upward passage of the gas, I provide a bubble plate denoted by 14, which extends inwardly from the walls of the casing close to but not in contact with the outer surface of the outermost cone-shaped member 10. An obstruction to the free flow of the gas upwardly through the apparatus is thus provided. The bubble plate is provided with a series of openings 15 from which extend a series of upwardly extending tubes or nozzles 16 (see more particularly Fig. 3), each of which has placed thereover a cap 17. The lower edge of the cap is serrated or provided with a series of

openings, and when the cap is placed in an inverted position over the tube 15, it stands in spaced relation to the tube and provides a passage for the gas upwardly through the

5 tube, thence downwardly and outwardly through the perforations or serrations formed in the lower edge of the cap or bell 16.

As will be seen upon reference to Fig. 2, 10 a multiplicity of these tubes and caps are employed.

It is designed to maintain the liquid at a level upon the plate 14 equal or substantially equal to the height of the tube 15, and to 15 that end I employ a series of drain pipes 17, the upper end of which extends through the bubble plate to a height practically equal to that of the tubes 15. Preferably the upper ends of the drain pipes 17 will terminate in 20 a plane slightly below that of the tubes 15 to ensure a slight head for the overflow. The lower end of the pipe 17 extends downwardly and dips into the liquid in the pan 12 therebelow, and as a consequence, the gas 25 cannot flow upwardly through this pipe 17 inasmuch as its lower end is at all times sealed by the liquid in the pan.

Extending around the bubble plate at a 30 point intermediate the outer series of tubes and caps and the wall of the casing is a baffle or surge-preventing plate 18. The lower edge of said plate is serrated and the plate stands parallel to the inner wall of the casing.

35 Instead of making the bubble caps round, they may be oblong, or in fact any desired shape, and in Fig. 4 such an oblong cap and a portion of its co-operating tube are illustrated.

40 In action the pan 12 having been filled to the required depth with liquid, motion is imparted to the shaft 6, and when the requisite speed has been attained, the liquid in the pan will be drawn upwardly by the 45 members 10 and sprayed outwardly, striking against the inner face of the casing and flowing downwardly onto the bubble plate 14. This plate will soon become covered with liquid to a depth substantially equal to 50 the height of the tube 15, the overflow pipe 17 preventing undue accumulation of the liquid on the plate. The sprayed liquid is prevented from surging over the plate and interfering with the proper action of the 55 bubble caps by the upstanding surge-breaking plate 18. The gas which is forced in through the port 2 must of necessity find its way up through the tubes 15 and beneath the bubble caps. This it does, passing down 60 through the liquid between the tube 15 and the overlying cap or bell 16, thence outwardly through the serrations in the lower edge of the cap, and then upwardly through the 65 body of liquid which is maintained at all times upon the bubble plate.

The gas under pressure passing upwardly through tubes 15 will depress the liquid inside the cap wall and will likewise raise the liquid slightly on the outside of the cap, thus producing the liquid head for overflow 70 through pipe (or pipes) 17, even though the upper end of the tubes and pipes should lie in the same plane. The gas ultimately passes into the eliminator chamber 4, around and in contact with the eliminator plates 5, 75 and finally to the outlet port 3.

While the structure above described sets up back pressure upon the gas, this may be taken care of by increasing the pressure upon the incoming gas and so proportioning 80 the parts, to wit, the size of the tubes 15, the caps, and the depth of liquid maintained upon the bubble plates, as to render the apparatus highly effective. Any back pressure which may exist is more than compensated for by the intimate contact which is produced between the gas and liquid aside from that which is produced between the gas and the spray as the former passes 85 through the latter.

90 What is claimed is:

1. In an apparatus of the character specified, the combination of a casing; means for spraying a liquid transversely within the casing; a receptacle to which the sprayed 95 liquid is returned and from which it is withdrawn by said spraying means; means for introducing gas into the casing and forcing the same upwardly through the spray; and means located intermediate the spraying 100 means and the receptacle for maintaining a body of liquid within the casing at a point below the path of the spray, through which body of liquid the gas must pass as it is forced upwardly through the casing.

105 2. In an apparatus of the character specified, the combination of a casing; means for spraying a liquid transversely within the casing; a receptacle to which the sprayed liquid is returned and from which it is withdrawn by said spraying means; means for introducing gas into the casing and forcing the same upwardly through the spray; and liquid sealed means located intermediate the spraying means and the receptacle through 110 which the gas must pass as it is forced upwardly through the casing.

115 3. In an apparatus of the character specified, the combination of a casing; a receptacle mounted therein, said receptacle standing in spaced relation to the inner surface of the casing; means for forcing gas upwardly through the casing and around the receptacle; means extending down into the receptacle and adapted to withdraw liquid 120 therefrom and to spray the same outwardly against the wall of the casing; a bubble plate extending transversely of the casing and located intermediate the spraying means and the receptacle, said plate serving to impede 125 the spray.

the direct upward flow of the gas through the casing; and means for maintaining liquid on said bubble plate at a predetermined level.

4. In an apparatus of the character specified, the combination of a casing; a receptacle mounted therein in spaced relation to the walls of the casing; a plate extending transversely of the casing and at a point above the receptacle; a series of tubes extending upwardly from openings formed in the plate; a cap overlying each of said tubes, the lower edge of each cap being serrated; a drain pipe extending from the plate to the receptacle; and means for drawing liquid from the receptacle and spraying it outwardly above the plate.

5. In an apparatus of the character specified, the combination of a casing; a receptacle mounted therein in spaced relation to the walls of the casing; a plate extending transversely of the casing and at a point above the receptacle; a series of tubes extending upwardly from openings formed in the plate; a cap overlying each of said tubes, the lower edge of each cap being serrated, a drain pipe extending from the plate to the receptacle; means for drawing liquid from the receptacle and spraying it outwardly above the plate; and a surge-preventing

6. In an apparatus of the character specified, the combination of a casing; a rotatable shaft extending upwardly therethrough; a receptacle extending transversely of the casing and spaced from the walls thereof; means secured to the shaft for withdrawing liquid from the receptacle and spraying the same laterally toward the wall of the cas-

ing; and a perforate plate extending inwardly from the casing at a point above the receptacle and below the path of the spray, said plate receiving the sprayed liquid where- 45 by intimate contact is had between such liquid and the gas as the latter is forced upwardly through the perforations.

7. In an apparatus of the character specified, the combination of a casing; a rotatable 50 shaft extending upwardly therethrough; a receptacle extending transversely of the casing and spaced from the walls thereof; means secured to the shaft for withdrawing liquid from the receptacle and spraying the 55 same laterally toward the wall of the casing; a plate extending inwardly from the casing at a point above the receptacle; means associated therewith for securing intimate contact between the liquid which flows thereon 60 from the spray and gas which is forced upwardly through the apparatus; and means preventing the liquid from surging over the plate.

8. In an apparatus of the character specified, the combination of a casing; a receptacle mounted therein, said receptacle standing in spaced relation to the inner surface of the casing; means for forcing gas upwardly through the casing and around the recep- 70 tacle; means extending down into the receptacle and adapted to withdraw liquid therefrom and to spray the same upwardly against the wall of the casing; and a bubble plate extending transversely of the casing 75 and located intermediate the spraying means and the receptacle, said plate serving to impede the direct upward flow of the gas through the casing.

In testimony whereof I have signed my 80 name to this specification.

FREDERICK H. WAGNER.
